GLUING MACHINE

Application filed September 14, 1928. Serial No. 306,085.

This invention relates to machines for applying adhesive to the surface of sheet material such as labels, paper box blanks, paper novelties and so forth, in an even as well as a smooth manner.

Primarily I aim to provide a compact and efficient manually operable "gluing" machine that is inexpensive to make, but which will apply such adhesive to sheet material economically, with attendant saving of time and labor.

Another object is to provide a machine of the type referred to that is easy to dismantle for cleaning, repair, or adjustment to accommodate differing service conditions.

The foregoing and other features of advantage are secured in the machine herein illustrated and described, while the appended claims particularly point out the alleged features of novelty.

In the drawings:—

Fig. I is a perspective view of my novel manually operable gluing machine, with a cover element removed to better disclose otherwise hidden details.

Fig. II is a sectional view, taken approximately as indicated by the arrowed plane designated II—II in Fig. I.

Fig. III is a top plan view of the machine, with parts broken away to clearly illustrate the drive mechanism.

Fig. IV is a front elevation with a fragment broken away to show a portion of the feed device in full lines.

Fig. V is a detail illustration of a modified form of feed device.

Fig. VI is a sectional view similar to Fig. II, but incorporating a modified form of picker means, hereinafter fully explained; and,

Fig. VII is a fragmentary plan view of the picker means illustrated in the preceding figure.

Referring more in detail to the drawings, my novel gluing machine comprises a rectangularly configured container or tank 8, having a dished bottom 9 provided with feet 10. This container or tank 8 is formed with a pocket 11, set apart therefrom by an integral partition 12, and opposed offsets 13 having

vertically directed slots 14, for a purpose later on explained. Journaled transversely in the container 8 is a hollow drum or gluing roll 15 which is journaled for free rotation by means of a bearing screw 16 at one end, and a boss 17 at the other freely passing through a cut out 18 of the partition 12, and fitted with a removable crank handle 19. Integral with, or securely attached to, the gluing roll boss 17 is a spur gear 20 meshing with a gear 21 on the adjacent end of the feed device, comprehensively designated 22. This feed device 22 comprises a spindle 23 having reduced ends, adapted for free rotation in the vertically directed slots 14 of the container offsets 13, that is, conveniently, fitted with a hard wood—or other appropriate—roll 24, having spaced grooves 25 receiving round-section rubber bands 26, which latter project beyond the perimetric surface of said roll, as clearly shown in Figs. I and IV.

Referring now to Figs. V and VI, which show a modified form of the feed device 22, it will be seen the same comprises a shaft 27, bearing a series of V-grooved disks 28 main-

tained in proper relation by means of intervening spacers 29, which are securely clamped together through the medium of a cotter pin 30 at one end, with a lock sleeve 31 and nut 32 at the other end. Obviously the

round section rubber bands 26 are snapped into the V-grooves of the disks 28, and it will be apparent that, by releasing the lock sleeve 31, said disks can be removed for

cleaning or renewal of the rubber bands 26, while their number may be varied to accommodate different service requirements. At

attention is particularly drawn to the fact that the feed device 22 may be characterized as of the gravity type in that it acts upon the ma-

terial fed into the machine by its own weight, and consequent slight compression of the rubber bands 26; also, that there is no "pull" exerted on said material by the roll 15, other than the contact influence of the applied

glue, which is promptly released by the picker or stripping means, later on fully described.

Freely pivoted on the feed device spindle 22 is a pawl 33 adapted to engage the teeth of

the spur gear 20, thereby preventing back motion of the gluing roll 15, in an obvious manner, as will be best appreciated from Fig. II.

5 The means for evenly spreading or distributing the glue, conventionally indicated 34 in Figs. II and VI, comprises a horizontally-directed scraper-bar 35 having vertically directed terminal portions 36, pivoted at 10 one end on a pin 37 Fig. III integral with or fitted to an upstanding projection 38 of the partition 12, and at the other end to the reduced terminal of a screw 39, later on again referred to. Co-operative with the scraper-bar 35, through the medium of a T-shaped end 40 entering an aperture 41 therein, is a manipulator 42 having its other end angled at 43 and forked for engagement with the grooved inner end 44 of an adjusting 15 screw 45. Thus it will be understood by turning the screw 45, in the proper direction, that the scraper-bar 35 will be rocked on the pivots 37, 39 toward—or away from—the gluing roll 15 and the thickness of the film 20 of glue applied by said roll thereby adjusted.

25 46 is the feed table or plate which is formed along the outer edge with a curved lip 47 that abuts the complementarily sectioned flange 48 of the tank 8, spring-tongues 30 49 serving to clamp the same in position by snapping the underside of the relatively reduced part of said flange at 50, in an obvious manner. The feed plate 46 is downwardly inclined along its inner portion and slotted to provide a series of tongues 51 with their ends preferably rounded; which, when said plate is in position, intervene the rubber bands 26 and extend into close proximity 35 with the peripheral surface of the gluing roll 15. It is also to be noted that the terminal tongues 51 of the series freely pass between the vertical extensions 36 of the scraper-bar 35, and thereby serve to maintain the same engaged with the pivots 37, 39.

40 In conjunction with the improved gluing machine, I provide a novel "picker" or stripping attachment which functions to promptly detach or release the sheet material from the roll 15, as fast as it is glued. This attachment comprises a spindle or rod 52 having diametric holes 53 near its ends, whereby it is seated on shouldered pins 54, secured in the tank walls. Freely supported by the 45 rod 52 are a series of comparatively-thin picker or stripping elements 55, of the configuration best shown in Fig. II, which are maintained in spaced relation by intervening and end sleeves 56, 57, and 58, respectively; the latter two being secured to the rod 52 by cotter pins 59, in an obvious manner. Attention, however, is directed to the fact that the stripper elements 55 are afforded a small degree of lateral clearance with respect to the sleeves 58; so that, as the gluing

50 roll 15 is rotated, they may slightly vibrate laterally of the machine and thereby prevent the formation of un-glued lines on the material as it leaves said gluing roll.

55 Instead of the stripper device described in the preceding paragraph I may employ the means shown by Figs. VI and VII, which consists of a plate 60 having a rolled edge and spring tongues 61, analogous to those set forth in connection with the feed plate 46, for gripping the tank flange 62 at the back of the machine. This plate 60 is conveniently provided along its inner edge with spaced fingers 63 that are slightly inclined downwards and formed with upwardly angled "picker" or stripping tongues 64 which barely touch or impinge the gluing roll 15, as conventionally indicated in Fig. VI by the dark shade line, and which function to remove the sheet material from said roll, in the manner hereinbefore explained. It is to be noted, however, that the just described form of stripper means is substantially rigid, and better adapted to the gluing of the heavier materials.

60 65 is a cover plate of arcuate cross-section that is provided with end projections or flanges 66, having slots 67 therein, whereby said plate is mounted over the feed device 22, and clamped to the offsets 13, through the medium of the screw 39 and a second screw 68, in an obvious manner.

65 From the foregoing it is thought the use and operation of my improved gluing machine will be well understood, but it may be here remarked that the feed plate 46 is first removed and the tank 8 filled with glue to within about one-quarter of an inch below the spreader or scraper-bar 35. The screw 45 is next adjusted until the bar 35 is positioned relative to the applying roll 15, so that the latter carries up a uniformly thin film of glue. The feed plate 46 is replaced and properly centered so that it does not bind either of the scraper-bar end extensions 36, whereupon the machine is ready for operation, by consecutively placing the elements to be glued on the plate 46, and from which they are drawn by the feed device 22 and pass over the roll 15, with subsequent removal therefrom by the strippers 55, or 64.

70 When it is desired to cleanse the machine, the cover plate 65 is removed by slackening the screws 39 and 68. The feed device 22 is then lifted from its bearings, the stripper means 55 or 64 bodily removed, while the handle 19 and bearing screw 16 are withdrawn, whereupon the gluing drum 15 can be lifted out and washed. Obviously, a reverse sequence of operations takes place in re-assembling the machine; and while I have particularly described the illustrated embodiments somewhat specifically, it is to be understood that structural changes or variations in the relative aggroupment of the sev-

eral co-operative means may be resorted to without transgressing the scope of the appended claims.

Having thus described my invention, what I claim is:

5. 1. The combination in a machine of the type described of a container for adhesive embodying an integrally-formed partitioned-off pocket; a manually-rotatable applicator drum journaled in the container with a drive gear located in the pocket; a pivoted bail-like scraper-bar with an adjustable manipulator-link adapted to regulate the thickness of adhesive applied by said drum; a feeding-in plate having tongues projecting into proximity with said drum, and a non-contacting co-operative circumferentially-ribbed feed roll driven by the applicator drum gear; and vibratory stripper means, removable as a unit, engaging the applicator drum to separate material therefrom as rapidly as it is coated with adhesive.
10. 2. The combination in a machine of the type described of a container for adhesive embodying an integrally-formed partitioned-off pocket; a manually-rotatable applicator drum journaled in the container with a drive gear located in the pocket; adjustable means comprising a pivoted bail-like scraper-bar and a manipulator link having a T-shaped end engaged therewith, said link having its other end angled-and-forked for movement by an adjuster screw; a feeding-in plate having tongues projecting into proximity with said drum, and a non-contacting co-operative circumferentially-ribbed feed roll driven by the applicator drum gear; and vibratory stripper means, removable as a unit, engaging the applicator drum to separate material therefrom as rapidly as it is coated with adhesive.
15. 3. The combination in a machine of the type described of a container for adhesive embodying an integrally-formed partitioned-off pocket; a manually-rotatable applicator drum journaled in the container with a driving gear located in the pocket; a pivoted bail-like scraper-bar and adjustable manipulator-link adapted to regulate the thickness of adhesive applied by said drum; a plate having slightly inclined tongues, with their free ends rounded, projecting into proximity with the applicator drum, and a roll having spaced resilient annuli co-operatively intervening said tongues, to feed-in the material for application of adhesive thereto; and vibratory stripper means, removable as a unit, engaging the applicator drum to separate material therefrom as rapidly as it is coated with adhesive.
20. 4. The combination in a machine of the type described of a container for adhesive embodying an integrally-formed partitioned-off pocket; a manually-rotatable applicator drum journaled in the container with a drive gear located in the pocket; a pivoted bail-like scraper-bar and adjustable angled manipulator link adapted to regulate the thickness of adhesive applied by said drum; a plate embodying slightly inclined tongues, with their free ends rounded, projecting into proximity with the applicator drum, and a roll incorporating spaced grooves with round-section rubber-bands co-operatively intervening said tongues, to feed-in material for application of adhesive thereto; and vibratory stripper means, removable as a unit, engaging the applicator drum to separate material therefrom as rapidly as it is coated with adhesive.
25. 5. The combination in a machine of the type described of a container for adhesive embodying an integrally-formed partitioned-off pocket; a manually-rotatable applicator drum journaled in the container with a driving gear located in the pocket; a pivoted bail-like scraper-bar and adjustable angled manipulator link adapted to regulate the thickness of adhesive applied by said drum; a plate embodying slightly inclined tongues, with their free ends rounded, projecting into proximity with the applicator drum, and a feed device embodying a series of peripherally-grooved disks with fitted round-section rubber-bands co-operatively intervening said tongues to feed-in material for application of adhesive thereto; and vibratory stripper means, removable as a unit, engaging the applicator drum to separate material therefrom as rapidly as it is coated with adhesive.
30. 6. The combination in a machine of the type described of a container for adhesive including an integrally-formed partitioned-off pocket; a manually-rotatable applicator drum journaled in the container with a drive gear located in the pocket; adjustable means adapted to regulate the thickness of adhesive applied by said drum; non-contacting feed means driven by the applicator gear; and vibratory stripper means—removable as a unit—comprising a stationary element supporting comparatively thin fingers having a similar degree of lateral play, disposed edge-on relative to the applicator drum, and co-operative therewith, to remove the material as rapidly as it is coated with adhesive.
35. 7. The combination in a machine of the type described of a container for adhesive including an integrally-formed partitioned-off pocket; a manually-rotatable applicator drum journaled in the container with a drive gear located in the pocket; adjustable means adapted to regulate the thickness of adhesive applied by said drum; non-contacting feed means driven by the applicator gear; and vibratory stripper means—removable as a unit—comprising a stationary member supporting spaced pawl-like fingers having a small degree of lateral play, the tips whereof engage the applicator drum and serve to lift

material therefrom as rapidly as it is coated with the adhesive.

8. The combination in a machine of the type described of a container for adhesive and embodying a partitioned-off pocket; a manually-rotatable drum journaled in the container with a drive gear located in the pocket; adjustable means adapted to regulate the thickness of adhesive applied by said drum; a feeding-in plate having tongues projecting into proximity with said drum, and a non-contacting co-operative circumferentially-ribbed feed roll driven by the applicator gear; slightly vibratory stripper means—
10 removable as a unit—engaging the applicator drum to separate material therefrom as rapidly as it is coated with adhesive; a removable arcuate section cover mounted over the feed device aforesaid; and means whereby the machine may be operated and restrained against back motion.

In testimony whereof, I have hereunto signed my name at Allentown, county of Lehigh, Pennsylvania, this 4th day of September, 1928.

CHARLES S. PRICE.
